FOOD PACKAGING TRAY

Donald K. Jewell, Chicago, Ill., assignor to Lincoln
Manufacturing Company, Inc.

Filed Jan. 18, 1971, Ser. No. 107,615

Term of patent 14 years

Int. Cl. D9—03

U.S. Cl. D9—185

FIG. 1

FIG. 2

FIG. 3

FIG. 4

FIG. 1 is a bottom plan view of a food packaging tray showing my new design;

FIG. 2 is a top perspective view thereof showing one side and end, the other end being substantially similar;

FIG. 3 is an enlarged section taken on line 3—3 of FIG. 2 and

FIG. 4 is an enlarged section taken on line 4—4 of FIG. 2.

I claim:

The ornamental design for a food packaging tray, substantially as shown and described.
